CLAIM

The ornamental design for a semiconductor device, as shown and described.

DESCRIPTION

FIG. 1 is a front, top, right perspective view of a semiconductor device showing my new design;

FIG. 2 is a front, bottom, right perspective view thereof; and FIG. 3 is a rear, bottom, left perspective view thereof;

FIG. 4 is a front elevational view thereof;

FIG. 5 is a rear elevational view thereof;

FIG. 6 is a right side elevation view thereof, a left side elevational view being a mirror image;

FIG. 7 is a top plan view thereof; and,

FIG. 8 is a bottom plan view thereof.

The broken lines showing of the unclaimed portions of the semiconductor device form no part of the claimed design.
